UNITED STATES PATENT OFFICE.

JOHN M. CROWE, OF COVINGTON, KENTUCKY.

RIVET-CUTTING GUN.

Application filed May 3, 1923. Serial No. 636,490.

This invention relates to improvements in rivet cutting guns.

The objects of this invention are to provide an improved handle for a rivet cutting gun; and to provide means for locking the cap closure of the valve chamber in assembled position.

Further objects of the invention will appear from the following description and 10 claims when considered together with the drawings.

Fig. 1 is a longitudinal sectional view of my improved device; Fig. 2 is a plan view of the same; Fig. 3 is a detail sectional view 15 taken on line 3—3, of Figs. 1 and 2; Fig. 4 is a diagrammatic view illustrating the manner of connecting and disconnecting the pipe; and Fig. 5 is a detail view showing the valve and valve chamber.

20 The barrel 1 of the rivet cutting gun is provided with the usual piston 2 and has connected in any suitable manner at its lower end the tool 3, while at its upper end there is connected by means of screw thread engagement the valve casing 4. The elbow connections 5 and 6 are provided at the upper and lower ends of the pipe 7 for connecting the same to the valve chamber, and the lower end of the barrel 1 respectively, so as to afford 25 30 air pressure on the two sides of the piston according to the well known operation of the gun.

The pipe 7 is bent as indicated at the points 8 so that when in secured position the main 35 or middle portion of the pipe extends in close proximity to the barrel 1 and is maintained in such position by means of the curved strap 9 which is hinged at 10 to the bracket 11 provided upon the barrel, the other end of the 40 strap 9 being detachably secured at 12 by means of a cotter pin to the other side of the bracket 11. The upper surface of the bracket 11 has a curvature which is described upon the axis of the upper portions 8^a of the pipe 45 so that upon removing the cotter pin and raising the strap the pipe may be turned upwardly about the axis just now referred to. Slip joints are provided between the two ends of the pipe 7 and the elbow connections so that 50 the pipe is free to respond to the longitudinal vibrations which are set up by operation of the gun. This joint is clearly illustrated in the drawing and comprises in each case a shoulder 13 in line with the extreme end of the pipe but spaced slightly therefrom so as to allow a certain clearance for longitudinal 55

movement of the pipe in response to vibrations. The edge portion 14 of each of the elbows 5 and 6 is given a tapering form as illustrated in the drawing and corresponds substantially to a curvature about a center corresponding to the axis of the vertical arm of the elbow at the other end of the pipe, as illustrated in Fig. 4. Packing 15 is provided around the end of the pipe in each case and the joint is held tight by means of the annular screw threaded member 16 which engages the corresponding end of the elbow joint and secures the packing against the tapering end portion 14. Pipe 7 is of such length that when one end abuts the shoulder 13, the other end is flush with the inner edge of the tapered portion 14, whereby the following described assembly and disassembly are possible. With this arrangement it will be seen that upon releasing the strap 9 and upon unscrewing one of the members 16, as for instance the right hand one, as viewed in Fig. 1, the pipe can be disconnected at the right hand end by swinging the joint, which is still secured to the left hand end of the pipe, about its vertical axis and at the same time turning the elbow joint at the right hand end of the pipe about its vertical axis in the opposite direction so as to separate the right hand end of the pipe and the corresponding elbow joint. In other words, by following this operation, the freed end of the pipe will describe a curvature substantially the same as that of the tapered edge surface indicated by reference 90 numeral 14. This same operation may be performed at either end of the pipe as may be desired. Upon separating the joint at one end of the pipe, its other end can be slipped out of engagement. In assembling these parts, 95 the reverse operation is followed.

The improved handle comprises the cross bar 17 which extends through the arms 18. The lower ends of the arms 18 are secured to the valve casing at a point below the longitudinal axis of the barrel and extend rearwardly and upwardly as clearly shown in the drawing. The bar 17 extends through a plane above the longitudinal axis of the barrel and is held in the arms 18 by means of the shoulders 17^a of the enlarged hand grip portion. The free end portions of the arms 18, set in the cut out portions 19 provided in the casing 4 of the valve chamber and are provided with registering openings through which extends the bolt 20 for securing the same in position. The nut 21 is screwed on one end of the 100 105 110

bolt 20 which has head 22 and clamps in position against the casing 4 the lock member 23 which is provided with a plurality of lobes or projections 24. These projections 24 are 5 so formed as to engage in corresponding recesses or indentations 25 provided around the edge of the disk 26 which closes the valve chamber 26^a. This disk closure has the usual screw threaded flange engagement with the 10 wall of the valve chamber as indicated at 27. The valve 28^a which is of the usual tapering plug type is carried by the bolt 28 which carries at its one end the nut 29 and cotter pin 29^a and at its other end the operating 15 handle 30. The stops 31 determine the limit of movement of the handle 30 in the two directions corresponding to the two positions of the valve for controlling the air pressure to the upper and lower sides of the piston.

20 Thus it will be seen that I have provided a pipe connection which has effective connections at its two ends with the elbow joints and at the same time is free to respond to the vibrations which are set up along the 25 length of the gun due to the particular operation of the tool. As the result of this particular arrangement there is no danger of such vibrations shearing or loosening in any way the joint between the pipe and the connector members 5 and 6. Furthermore, the 30 means for securing the pipe 7 in clamped position and in close proximity to the barrel of the gun prevents this member against being used as a handle by the operator and thereby minimizes danger of such pipe member being 35 bent or torn from its connections. The intermediate portion of the bar 17 of my improved handle serves as a more convenient and reliable means of lifting and holding 40 the barrel with one hand and avoids the danger of the gun tilting or turning to one side as in the old familiar type of handle when lifted with one hand. This "spade" type of handle, which I have devised, is assisted 45 rather than opposed by gravity in steadying the cutting gun when lifting and handling the same with one hand since the weight of the gun might be considered as depending below or from the handle. In this way the

other hand is free and consequently the operation of the gun is greatly facilitated. Furthermore, the locking means for maintaining the disk closure of the valve chamber in secured position constitutes another advantage of my present invention. 50 55

What I claim is:—

1. In a rivet cutting gun structure, the combination of a piston barrel and piston, a valve chamber and a valve for controlling the operation of said piston, a closure for said valve chamber, a handle for supporting said barrel, means for locking said closure in position, and a single means for securing said handle and said locking means to the gun structure. 60 65

2. In a rivet cutting gun structure, the combination of a piston barrel and piston, a valve casing having a valve chamber, a valve in said chamber for controlling the operation of said piston, a closure for said valve chamber, means at one side of said chamber for locking said closure in position, a handle for supporting said barrel, and a single means for securing said locking means and said handle to the gun structure. 70 75

3. In a rivet cutting gun structure, the combination of a piston barrel and piston, a valve chamber and valve for controlling the operation of said piston, a closure for said valve chamber, means at one side of said chamber for locking said closure in position, a handle for supporting said barrel, and a single bolt for securing said locking means and said handle to the gun structure. 80

4. In a rivet cutting gun structure, the combination of a piston barrel and piston, a valve casing having a chamber, a valve in said chamber for controlling the operation of said piston, a closure for said valve chamber, means for locking said closure in position, a handle for supporting said barrel and having portions extending along opposite sides of said valve casing, and a single means for securing said locking means and said handle portions to said valve casing. 90 95

In testimony whereof I hereby affix my signature.

JOHN M. CROWE.
